UNITED STATES PATENT OFFICE.

ARI RÜLF, OF BRUSSELS, BELGIUM.

TOOL FOR BENDING PIPES OR FIGURED BARS.

992,807.

Specification of Letters Patent. Patented May 23, 1911.

Application filed December 26, 1907. Serial No. 408,142.

To all whom it may concern:

Be it known that I, ARI RÜLF, a citizen of Belgium, residing at Brussels, Belgium, have invented certain new and useful Improvements in Tools for Bending Pipes or Figured Bars, of which the following is a specification.

This invention has for its object a tool for bending pipes or figured bars of any kind.

With the new tool the pipe is bent around the circumference of the form-piece by a knee-lever consisting merely of two members joined together. The longer member is turnably journaled in the form-piece, while the short knee-piece jointed to the end of this member presses upon the pipe to be bent firmly and unmovably. When moving this lever, for instance by means of a handle fastened to the rear-prolongation of the short knee-piece, the pipe is by an always increasing knee-lever action pressed down with great force upon the form-piece, and this force becomes the greater the more the two united levers approach their respective dead points, so that shortly before and after passing the dead point the greatest bending force is exerted.

The invention is shown in the accompanying drawings, in which,

Figure 1 is a side elevation. Fig. 2 is an end view, parts being shown in section. Fig. 3 is an elevation showing the parts in a different position from that shown in Fig. 1. Fig. 4 is a detail. Figs. 5 and 6 are diagrammatic views. Fig. 7 is a plan view of the modification. Fig. 8 is an elevation thereof, and Fig. 9 is a detail.

The pipe *a* which is to be bent around the correspondingly figured circumference of the form-piece *b* is jammed in at one point of the circumference by means of the tie-screw *c*. The lever exerting the bending force merely consists of the two parts *d* and *i*. The arm *d* is turnably journaled in the form-piece by means of the center-bolt *f* and is, as shown in Fig. 2, formed by two fish-plates arranged at both sides of the form-piece, and whose ends are united with each other by the bolt *g*. On this bolt *g* the shorter arm *i* can be shifted by means of its slot *h*. The end of the arm *i* firmly sits in a suitable manner against the pipe to be bent, for instance in the form shown in the drawing by means of a block *k*, which is provided with a V-shaped groove for put-

ting it on the pipe, and on the sides with two pins *l*. On these pins *l* rests the fork-shaped end of the short lever arm *i*. In this way the clamping or jamming-lever finds a supporting point on the pipe. If now this jamming-lever is turned forward in the direction shown by the arrow by means of the handle *e* provided at its rear end, the pins *l* form a fixed pivot on the pipe and the jamming-lever causes the arm *d* to turn to a certain extent (Fig. 3). In consequence of this there is caused by the joint movement of the arm *d* and the lever *i* a corresponding partial bending of the pipe *a* around the circumference of the form-piece. The more the knee-lever consisting of the parts *d* and *i* approaches its dead point (Fig. 3) the greater becomes the bending force exerted on the pipe. This can be seen more especially when comparing the two diagrammatic Figs. 5 and 6, according to which the force *P*, which tends to turn the arm *d*, is divided, in the direction of the two arms *d* and *i*, into two component forces *P*¹ and *P*². The component force *P*², which represents the pressure exerted on the pipe becomes constantly greater as the bending proceeds (Fig. 6) and finally nearly infinitely great, so that even the strongest pipes can be bent by hand.

The flattening of the pipes which frequently occurs when they are bent in a proportionally small circle can be prevented even without any filling with sand, or the like, in a simple way by letting, as shown in Fig. 4, the lateral borders *m* of the form-piece project a little farther than half the cross-section of the pipes. In this way the pipe enters deeply into the groove, whereby the flattening is made impossible. As soon as the dead point of the jamming lever-work has been reached or passed, the lever *e* is turned back again and the end of the same, that is to say the pressing-piece *k*, is set upon another, farther point of the pipe and the described process is repeated. The slot *h* allows, if necessary, to lengthen the short arm of the jamming-lever by using pieces which can be inserted into the slot *h*, so that, if desired, it is possible to advance the same a great distance on the pipe, whereby especially with small diameters and bending radii the bending of the pipe up to one or two right angles can be performed by a single movement of the jamming-lever.

Another form of the pipe-bender, which

is suited for bending pipes of different widths, is illustrated in Figs. 7 to 9. The form-piece *b* is provided with grooves *a*¹, *a*², *a*³, *a*⁴, arranged in steps one above the other, in order to be able to bend pipes of different diameters on one and the same form-piece, without having to exchange any parts. These steps are produced by making the bending-radii toward the top smaller according to the smaller diameter of the pipes. The form-piece has an octangular projection *n* by means of which it can be clamped or jammed in the vise or in the pipe-vise; for the ordinary vise the vertical surfaces are used, for the pipe-vise the slanting surfaces.

On the vertical axle *f* in the form-piece is pivotally journaled the lever-arm *d* formed by an upper and a lower fish-plate, whose ends are united by the likewise vertical axle *g*. On the latter is pivotally journaled the jamming-lever *e*, *i* by means of a longitudinal slot *h*, in order to be able to lengthen and shorten, as required, the end which is placed upon the pipe. To this end the walls of the slot are provided with grooves *o* at corresponding intervals, into which the wedge-piece *p* is pushed against which sets the axle *g*. The jamming-lever is put upon the pipe by means of the clamping-piece *k* with a V-shaped groove.

For holding fast the pipe on the form-piece serves the clamping-device formed by the hinge-joint *s*, the bow *t* and clamping-screw *u*. The hinge-joint *s* is fastened to the lower part of the form-piece. In the same is journaled, by means of the bolt *v*, the bow *t*, which ascends on the form-piece and is provided with corresponding grooves, in order to encompass the pipes. It terminates at the top in a vertical part against which sets the clamping-screw *u*. The latter sits in a hook-shaped piece *w*, which is pivotally journaled on the axle *f* below the upper fish-plate *d*. Owing to this arrangement the bow can be completely turned up, whereby the inserting and removing of the pipe is greatly facilitated.

What I claim as my invention and desire to secure by United States Letters Patent is:

1. In a tool for bending pipes or figured bars, a form-piece *b* around the circum-

ference of which the pipe is bent by a knee-lever work consisting of two members *d* and *i* united by a joint, whose longer member *d* is turnably journaled in the form-piece, and whose shorter knee-piece *i* is placed upon the pipe to be bent in a manner that it is unmovable on the same, so that during the movement of the lever-work the pipe is, in consequence of the constantly increasing action of the knee-lever, pressed down with great force upon the form-piece, substantially as set forth.

2. In a tool for bending pipes or figured bars, a short knee-piece *i* journaled by means of a slot *h* on the end-pin *g* of the arm *d*, in order to allow of putting the clamping-lever upon the pipe to be bent at a shorter or greater distance, according to the thickness and curvature of the pipe, substantially as set forth.

3. A tool for bending pipes comprising a form piece around the circumference of which the pipe is adapted to be bent, a lever *d* pivoted to the form piece, a second lever having a slot intermediate its ends, a pin passing through said slot and carried by the end of the lever *d*, said slot having grooves in its walls and a wedge fitting in said grooves to hold the pin in any desired position within the slot.

4. A tool for bending pipes comprising a form piece around the circumference of which the pipe is adapted to be bent, a lever *d* pivoted to the form piece, and a second lever having a movable connection with the first lever intermediate its end, one end of said second lever being adapted to immovably engage with the pipe to be bent.

5. A tool for bending pipes comprising a form piece, a lever *d* pivoted thereto, a second lever *e* having a slot intermediate its ends, and a pivot carried by the lever *d* and passing through said slot, one end of the lever *e* being adapted to immovably engage the pipe to be bent.

In witness whereof I have hereunto set my hand in presence of two witnesses.

ARI RÜLF.
